(57) CLAIM

The ornamental design for a feminine care package, as shown and described.

DESCRIPTION

FIG. 1 is a front perspective view of a feminine care package showing our new design;

FIG. 2 is a back view thereof;

FIG. 3 is a first side elevational view thereof;

FIG. 4 is a second side elevational view thereof;

FIG. 5 is a top plan view thereof; and,

FIG. 6 is a bottom plan view thereof.

In the drawings, the broken lines represent unclaimed environmental structure.
